UNITED STATES PATENT OFFICE.

CHARLES H. AMIDON, OF MILLER'S FALLS, MASSACHUSETTS.

IMPROVEMENT IN DRILL AND BIT STOCKS.

Specification forming part of Letters Patent No. **140,451**, dated July 1, 1873; application filed October 31, 1872.

To all whom it may concern:

Be it known that I, CHARLES H. AMIDON, of Miller's Falls, in the county of Franklin and State of Massachusetts, have invented a new and useful Improvement in Drill and Bit Stocks; and I do hereby declare the following to be a full, clear, and exact description of the same, reference being had to the accompanying drawings, in which—

Figure 1 is a perspective view of my invention. Fig. 2 is a longitudinal section of the same. Fig. 3 is a cross-section of the same. Fig. 4 is a longitudinal section of revolving head. Fig. 5 are diagrams showing different positions. Fig. 6 is an end view of jaws and brace-head.

The first part of my invention relates to that class of bit-stocks wherein the socket to receive the head or shank of the bit or other tool is provided with jaws having independent movements, and capable of conforming to any plane-surfaced solid, whatever may be the angular relations of said surfaces, for the purpose of gripping the same firmly, irrespective of said irregularities. Heretofore said jaws have been constructed to move at either or both ends, and to embrace the tool through nearly or quite the whole length of said jaws, and, consequently, they have not been constructed to move upon centers. Therefore, from various causes—such as sticking or the presence of obstructing substances—they are in a greater or less degree uncertain in their action. My invention is designed to accomplish the same results without being subject to the same practical objections; it, therefore, consists in two sets of jaws independently pivoted, base to base, to the brace-head, and arranged to act against the head or shank of the tool at both ends thereof, and, therefore, capable of gripping said head with equal firmness, whatever may be its form, whether plain or irregular, angular or cylindrical, in cross-section. It also consists in two sleeves having relative motions in opposite directions, so as simultaneously to compress all the several jaws.

That others may fully understand this part of my invention, I will particularly describe it.

A A A' A' are the jaws arranged in pairs between which the tool is to be secured. They are pivoted, base to base, to the slotted head

B, one pair, A A, points forward, and the other pair, A' A', points backward, as shown. They have independent movements, and when any object is placed between them, they are capable of moving toward said object until in contact therewith. When said jaws are moved equally from opposite directions, they will meet at the axial line, and whatever object is interposed between them will be held centrally. The required movements of the jaws are effected by means of two sleeves, C D, moving the one upon the other with a screw-thread surrounding the head B, and having relative movements independent of said head, which will cause the simultaneous compression or release of the jaws A A A' A'. The outer sleeve C moves in a screw-thread cut on the outer surface of sleeve D, and the latter is provided with a pin, d, which moves in a groove, b, in the head B, so that, while the sleeve C advances with a spiral movement or screw, the sleeve D advances with a rectilinear movement only. Said sleeves both inclose the free ends of their respective sets of jaws, and act upon them, as shown. When any object having a uniform diameter is placed between said jaws, and the sleeve C is rotated so as to compress the jaws A A, they will only cease to be compressed when they are in contact with the object interposed. Such rotation of the sleeve C causes, at the same time, a rectilinear movement of sleeve D and a simultaneous compression of jaws A' A'. When the object interposed is irregular or tapering, one set of jaws will be in contact therewith sooner than the other set having a less distance through which to move, and an endwise movement of the head B may then take place. The movement of sleeve D will be accelerated, and the forcible or gripping compression of the jaws will not occur until both sets are equally in contact with the object interposed. In Fig. 5 is represented the range of various positions which said jaws may assume; and it is, therefore, evident that, whether the object interposed is of uniform or varying diameter, plain or irregular, said jaws will firmly gripe and hold it.

The second part of my invention relates to the method of attaching the rotating cap, and it consists in a flanged sleeve which passes through said cap and incloses the terminal

spindle, to which it is secured by a screw-coupler. E is the flanged sleeve fitted to a central orifice in the cap F. Its outer surface near its end, is provided with a screw-thread to engage with the screw-socket G, which is permanently attached to the spindle H, but free to revolve thereon. I prefer to place a wooden quill, I, on the spindle H, and said quill fills snugly the interior of the sleeve E. Said quill and socket G are both retained upon said spindle by a head, riveted or otherwise secured to the end of said spindle.

By this method of construction the cap F is capable of great ease and truth of motion, and, while securely retained in position, it may, if required, be easily detached.

The third part of my invention relates to the gearing, its arrangement and manner of attachment, whereby the bit-stock may be readily changed into a hand-drill. To accomplish this purpose the shank J of the bit-stock is perforated axially, so as to receive a spindle, K, to the outer end of which the head, jaws, and sleeves A B C D are attached. The spindle K may be secured in place by a nut or other convenient means. At the end of the shank J there is a beveled wheel, L, and on the spindle K there is a beveled wheel, M, and motion is communicated from the former to the latter by means of a double intermediate bevel-wheel, N, whereby the spindle K is speeded up as much as may be desired. The intermediate wheel N is mounted upon a spindle, O, to which the handle P may be attached; and because, when the brace is employed for boring-bits, it is desirable that the intermediate wheel N and the handle should be removed. I construct the spindle O as shown in Figs. 2 and 3—that is to say, I hinge two pieces, o o, and bore out immediately below the hinge a bearing to fit the shank J, as shown, and below said bearing a shank, Q, is formed, divided in two parts longitudinally, as shown in Fig. 3, and provided with a screw-thread cut on its outer surface. This shank Q screws into the spindle O, which forms the bearing for the intermediate wheel N, and also serves to secure the two parts of the shank Q together. Thus the handle P and the intermediate wheel N may be easily and readily removed from the brace. At such time a pin should be inserted through the hole h to prevent the shank J and spindle K from turning one upon the other while being used for boring. By leaving the intermediate wheel N in place, however, the pin in the hole h will not be required, as said intermediate wheel will then revolve with the brace, and no different movement will be communicated to the spindle K. The fourth part of

my invention relates to a detachable frame, in which the brace may be mounted, so as to afford additional facilities for managing and executing the work. To this end I provide a frame, S, with a seat, f, at one end, to receive and hold the revolving cap F, and a hole, T, through which the shank R of the sleeve O may pass, when, by screwing on the handle P, the brace is firmly secured in the frame. Said frame may then be mounted upon a stationary pivot inserted through the hole T, or it may be secured between the jaws of a vice, as shown in Fig. 1. A tail-stock or table, U, may be mounted at the opposite end of the frame S, and may be adjusted back and forth thereon and secured by means of a binding-screw, n.

The work is fed to the drill or other boring tool by means of a hand-lever, V, linked to said tail-stock, substantially as shown and described.

Having described my invention, what I claim as new, is—

1. An adjustable socket formed by and between two sets of jaws, A A' A', independently pivoted, base to base, to the head B, and actuated by the means described or their equivalents.

2. The separate sets of jaws A A' A', independently pivoted, base to base, to the head B, combined with a sleeve, D, having a rectilinear movement on the spline-groove b, and the sleeve C having a circular advancing motion on the screw-thread to actuate the said jaws, in the manner described.

3. The spindle H, with the quill I and loose screw-socket G, combined with the hollow coupler-sleeve E fitted over said spindle and quill, and engaging with said screw-socket to connect the cap F with the brace, as set forth.

4. The sleeve-spindle O combined with the jointed shank Q o o, as described, so as to be readily detachable, as set forth.

5. The combination of the pinion L on the shank J, intermediate double gear-wheel N, and pinion M on the spindle K, carrying the bit-head B, substantially as and for the purpose shown and described.

6. The frame S constructed in the manner described, with a rest, f, for the cap F, combined with an adjustable feeding device, U V, so that the whole may be secured in a common vise, and operated in the manner described.

CHARLES H. AMIDON.
